UNITED STATES PATENT OFFICE

169,551

DOORKNOB

Marron Kendrick, Atherton, Calif., assignor to
Schlage Lock Company, a corporation

Application June 7, 1952, Serial No. 20,073

Term of patent 14 years

(Cl. D50—3)

To all whom it may concern:

Be it known that I, Marron Kendrick, a citizen of the United States and a resident of Atherton, county of San Mateo, State of California, have invented a new, original, and ornamental Design for a Doorknob, of which the following is a specification, reference being had to the accompanying drawing, forming a part thereof.

Figure 1 is a perspective view of a doorknob showing my new design;

Figure 2 is a front elevation thereof;

Figure 3 is a side elevation thereof; and

Figure 4 is a rear elevation thereof.

I claim:

The ornamental design for a doorknob, as shown.

MARRON KENDRICK.
